WINDOW MOUNTED AIR-CONDITIONING UNIT

Arthur H. Eberhart, Springfield, Mass., assignor
to Westinghouse Electric Corporation, East
Pittsburgh, Pa., a corporation of Pennsylvania

Application May 1, 1946, Serial No. 666,381

7 Claims. (Cl. 98—98)

1

This invention relates to an air conditioning unit adapted to be mounted in the window opening of a room, the air of which is to be conditioned.

More specifically, the invention relates to an air conditioning unit especially adapted to be mounted in the upper and less useful portion of the window opening, whereby the lower and more useful portion of the window opening remains unobstructed.

It has heretofore been proposed to mount an air conditioning unit in the upper portion of a window opening, as shown, for example, in the Kramer Patent No. 1,706,852. In this construction, however, the window sashes cannot be moved far enough to completely close the window opening without disconnecting and removing the unit.

It is, therefore, one object of the invention to produce improved mounting means for mounting the air conditioning unit in the upper portion of a window opening, whereby the window opening may be completely closed without the necessity of removing or disconnecting the unit, or any material part thereof from the window.

Furthermore, the arrangement of the operative parts of the Kramer structure and the manner in which it is mounted are such that the unit extends horizontally along its entire length into the room, thus detracting from the appearance of the room.

My improved air conditioning unit is so constructed that, when it is mounted in the upper portion of the window opening by the mounting means of my invention, it extends partly horizontally into the room and partly upwardly toward the ceiling of the room and adjacent the wall of the room above the window opening so as to minimize the protrusion of the unit horizontally into the room and thus improve the appearance of the installation.

Because, in the prior art construction referred to, the unit extends horizontally into the room along its entire length, heavy operating parts, such as the compressor, the evaporator and the condenser are disposed relatively remote from the window structure to which the unit is secured. This increases the turning moment of the unit and necessitates the use of bulky fastening means to support the unit, and may necessitate

2

the use of means for reinforcing the window structure itself to enable it to withstand the resulting strain.

It is, therefore, a still further object of the invention to produce an improved air conditioning unit, the component parts of which are so arranged as to bring the center of gravity of the heavy operating parts relatively close to the window structure, thus reducing the turning moment of the unit and permitting the use of smaller and less conspicuous fastening and mounting means.

A still further object is to produce improved mounting means, whereby the turning moment of the unit is more widely distributed and more effectively resisted, thus permitting the use of relatively light parts and reducing the strain exerted on the frame of the window in which the unit is mounted.

A still further object of the invention is to produce improved mounting means whereby the air conditioning unit may be easily mounted with minimum effort and with minimum damage to, or marring of, the window structure.

A still further object of the invention is to produce improved means for effectively weather-proofing the portion of the window opening in which the window is mounted, said weather-proofing means being so constructed that it may be applied or removed independently of the unit and the mounting means.

These and other objects are effected by my invention as will be apparent from the following description and claims taken in connection with the accompanying drawings forming a part of this application, in which:

Fig. 1 is a perspective view of a portion of a room showing an air conditioning unit mounted in the upper portion of a window opening;

Fig. 2 is an enlarged diagrammatic view partly in section and partly in elevation of the upper portion of a window opening with the air conditioning unit mounted therein, this view being taken in the direction of the line II—II of Fig. 5;

Fig. 3 is a section on line III—III of Fig. 2;

Fig. 4 is an enlarged fragmentary view of a portion of Fig. 3 showing details of construction;

Fig. 5 is a view partly in section and partly in top plan view, certain parts being omitted;

Fig. 6 is an enlargement of a portion of Fig. 5 showing details of structure;

Fig. 7 is an enlarged fragmentary perspective view showing details of the mounting means construction; and

Fig. 8 is a diagram of forces involved.

Throughout this description, the terms "rear" and "front" are used with reference to an observer within the room, the term "rear" being used to designate the side of the unit which faces the exterior of the room, and the term "front" being used to designate the side of the unit which faces the interior of the room.

In Fig. 1 of the drawings there is shown a portion of a room, one wall of which is provided with a window opening defined by a bottom sill 10, a top sill 12 and side jambs 14. The window opening is adapted to be closed by means of inner and outer conventional sashes 16 and 18, respectively, which are slideable in the usual sash grooves 20.

According to my invention, the air conditioning unit is generally L-shaped, with the horizontal limb of the L extending from the upper portion of the window opening horizontally inwardly into the room, and with the vertical limb of the L extending upwardly, adjacent and parallel to the wall of the room above the window opening, toward the ceiling of the room, as best shown in Figs. 1 and 3. By this construction of the unit, and by this arrangement of the unit relative to the window opening, the unit is rendered inconspicuous and the obstruction of the window opening and of the space adjacent the window is reduced. These advantages, and the particularly attractive appearance produced can be appreciated from an inspection of Fig. 1.

The air conditioning unit includes a compressor 22 for compressing and liquefying the refrigerant, a condenser 24 connected to the compressor for receiving and cooling the liquefied refrigerant, and evaporator 26 connected to the condenser by any suitable expansion means for evaporating the refrigerant and extracting heat from the air to be cooled. A motor 28 operates a blower 30 for moving air to the condenser and a blower 32 for moving the air to be cooled into contact with the evaporator. The evaporator blower 32 is adapted to draw outside air through a portion of the window opening, or room air through an opening 34 formed in the rear wall of the unit casing above the window, or a mixture of outside air and room air. The air conditioned by the evaporator is discharged into the room through an outlet 36 formed in the front wall of the unit casing.

The condenser fan is adapted to draw outside air through a portion of the window opening, or it can draw room air through an opening 38, also formed in the rear wall of the unit casing above the window, or a mixture of outside air and room air, for cooling the condenser. The air moved by the fan 30 is discharged onto the condenser and then to the outside atmosphere through the window opening.

Suitable dampers, not shown, are provided for controlling the openings 34 and 38 and for controlling the admission of outside air into the unit by the evaporator blower 32. The dampers referred to may be operated by any suitable means, such as cords 39 engaging pulleys 40 operatively connected to the shafts or rods carrying the dampers.

The operative parts of the air conditioning unit described are enclosed by a decorative removable

cover 44, the back side of which is completely open, and the front face of which is provided with the outlet 36, which may have a grille therein, and through which the air conditioned by the evaporator is discharged into the room. A screen 50 extends across the open end of the lower horizontal portion of the unit casing to keep insects and dirt out of the unit.

The unit mounting means embodying my invention includes a pair of stanchions or posts 52, preferably formed of pipe sections cut to fit the height of the window opening and having upper flattened portions 54 which correspond to the height of the unit. The stanchions 52 are positioned along the opposite side jambs of the window and are fastened to the bottom sill by means of cups 56 which are adapted to rest on the window sill. The cups 56 are rigidly secured to the bottom window sill so as to resist turning moment exerted at the lower ends of the stanchions. As shown, the cups 56 are held in position by plates 58 secured thereto and having pendant flanges 59 which are secured to the rear wall of the bottom window sill by screws 60. The cups 56 preferably, but not necessarily, detachably engage the lower ends of the stanchions.

By being positioned along the side jambs of the window, the stanchions 52 are rendered inconspicuous so as not to detract from the appearance of the room.

The flattened portions 54 of the stanchions are provided with rigidly secured, oppositely aligned upper and lower cups 62 and 64 for detachably engaging the opposite ends of upper and lower cross members 66 and 68, respectively. The cross members 66 and 68 coact with the stanchions 52 to support and position the unit relative to the upper portion of the window opening.

As shown, the upper cross member 66 has two or more bolts 70 passing therethrough with the inner ends of the bolts engaging brackets 72 secured to and forming part of the unit casing. The inner ends of the bolts also engage angle members 74 which extend from the bolts in opposite directions towards the side jambs of the window and are provided with tongues 75 adapted to engage openings 76 formed in tabs or extensions 77 carried by the vertical sides of the cover 44. To apply the cover to the unit and to retain it in position, the cover is merely slipped over the unit and moved toward the window until the tongues 75 fit into the openings 76. To remove the cover the tongues are pushed out of the openings and the cover is then withdrawn in the direction of the room.

In order to resist the turning moment of the unit exerted at the upper ends of the stanchions in clockwise direction as viewed in Fig. 3, I provide an elongated bracket 78 having a lower wall 79 which is engaged by the outer ends of the bolts 70. The bracket 78 also has an upper offset wall 80 which abuts against the back wall of the decorative inner window sill strip 81. The bracket 78 is secured to the upper window sill 12 by screws 82 which pass through the horizontal top wall 83 of the bracket and engage the upper window sill 12, as best shown in Figs. 2, 3 and 7.

In order to resist the turning moment exerted by the unit at the cross member 68 and to assist in proper positioning thereof relative to the window opening, that is, to insure that the unit has the desired angular relation to the vertical plane of the window opening, the bottom of the unit casing is provided with an angle member 84 and one or more adjusting screws 85 which threadedly

engage the pendant wall of the angle member 84 and the outer ends of which are adapted to abut against the lower cross member 68, as best shown in Fig. 4. Thus, upon mounting the unit in position, the adjusting screws 85 can be turned in the appropriate direction to move the lower end of the unit towards or away from the lower cross member 68, until the unit is at the desired angular position.

The lower cross member 68 also carries a pair of clips 86, one at each end thereof, for supporting a conventional, roller type window shade which can be used to occlude the window opening in the usual manner.

Assembly

When it is desired to mount an air conditioning unit of the type described in a window opening, the stanchions 52 and the cross members 66 and 68 are cut to the height and width of the window, respectively. The cross members are then inserted in the upper and lower cups 62 and 64 and the stanchions are positioned along the opposite side jambs of the window and secured to the bottom sill thereof by the screws 60. The bolts 70 are then inserted through the lower wall 79 of the bracket 78 and are passed through the upper cross member 66. In this position the wall 80 of the bracket 78 engages the rear wall of the upper sill strip 81 and the upper wall 83 of the bracket is secured to the upper sill 12 by the screws 82.

The unit is then lifted and presented to the upper portion of the window opening so as to cause the threaded ends of the bolts 70 to engage the brackets 72. Nuts are threaded onto the bolts 70 to hold the brackets 72, the member 66 and the wall 79 together. The brackets 74 are then mounted on the threaded ends of the bolts in position to engage the cover 54 when the cover is applied to the unit. Nuts are then used for preventing disengagement of the brackets 72 from the bolts 70. The adjustment screws 85 are turned in the appropriate direction so as to give the unit the desired position relative to the window opening.

To remove the unit, it is merely necessary to remove the brackets 74 and then to disengage the brackets 72 from the bolts 70. To remove the mounting means it is merely necessary to disengage the screws 60 and 82, whereupon the stanchions 52 and the upper and lower cross members 66 and 68 can be bodily removed from the window. It will be noted that, except for the engagement of the screws 60 and 82 with the lower and upper window sills, respectively, the wood-work of the window frame is not in any way marred or damaged. It will also be noted that the engagement of the wall 80 of the bracket 78 along a relatively large area of the upper sill strip 81 provides sufficient bearing surface over which the strain caused by turning moment of the unit is distributed so that the strain exerted on the strip 81, per unit area, is substantially reduced. This makes use of relatively light metal parts and enables the usual upper sill strip 81 to resist the turning moment of the unit without the need of special reinforcement.

As may be more clearly seen from diagrammatic Fig. 8, the horizontal forces applied to the window frame and the consequent strains of the latter are greatly reduced by the mounting means of the invention. The structure involves two separate sets of horizontal forces; first, the horizontal forces exerted by the unit on the stanchions 75 of the

or columns and, secondly, the horizontal forces exerted by the unit and column assembly on the window frame. With the center of gravity of the unit at C, then the gravity force W applies a clockwise moment WD about the axis A, producing a horizontal force K to the right at B, the force K being equal to

$$W\left(\frac{D}{E}\right)$$

10 This may also be expressed as $K=W \tan a$, since

$$\frac{D}{E}$$

15 is the tangent of the angle a. The gravity force also applies a clockwise moment WD about the axis B, producing a horizontal force L to the left at A, the force L also being equal to

$$W\left(\frac{D}{E}\right)$$

These forces are imposed on the cross arms 66 and 68 and on the stanchions, but they are not imposed on the window frame.

20 Considering now the horizontal forces imposed on the window frame, the clockwise moment WD about F produces a horizontal force M to the right at G, the force M being equal to

$$W\left(\frac{D}{H}\right)$$

25 or $W \tan b$, and the same moment WD about G produces a horizontal force N to the left at F, which is also equal to

$$W\left(\frac{D}{H}\right)$$

30 or $W \tan b$.

35 Since the moment arm H is great in relation to the moment arm D, the horizontal forces imposed on the window structure by the tilting moment are greatly reduced. It will be noted that these horizontal forces are reduced as the center of gravity is moved toward the window to reduce the arm D.

Weatherproofing means

40 My invention further includes means for effectively weatherproofing the portion of the window opening in which the unit is mounted. Preferably, the weatherproofing means is completely detachable from the unit and from the mounting means so that it may be easily applied to, or removed from, the window without in any way disturbing the installation of the air conditioning unit itself.

45 As best shown in Figs. 3 and 7, the weatherproofing means includes an upper cross member 87 which is as long as the unit. The upper cross member 87 is secured in position by means of one or more brackets 88, the lower ends of which are secured to the lower wall of the upper cross members by bolts 89. The upper ends of the brackets 88 are secured by the screws 82 which fasten the top wall 83 of the bracket 78 to the upper sill of the window. The upper cross member 87 is also provided with an inner upturned wall 90 to which is detachably secured a highly compressible gasket 91 which extends along the entire length of the cross member and which abuts the upper outer wall of the unit casing. 50 The upper edge of the upper cross member 87 enters the groove formed in the underside of the upper window sill between the inner sill strip 81 and the intermediate sill strip 92 and is disposed inwardly of and overlaps the front wall 70 of the strip 92.

The weatherproofing means also includes a lower cross member 93 for effecting a seal with the upper edge of the outer window sash 18, and a frame formed of a horizontal member 94 which supports the lower cross member 93, and side members 95 adapted to seal the junction between the sides of the unit and the side jambs of the window.

The lower cross member 93 is preferably in the nature of a molded rubber strip adapted to engage the upper window sash and is preferably provided with a pendant flange 93a which overhangs the outer wall of the sash, as best seen in Fig. 7. The rubber strip 93 is connected by a somewhat reduced portion 93b to an enlarged marginal portion 93c which is enclosed in a casing 96 with or without a reinforcing member 97. The reduced portion 93b serves as a hinge between the body of the strip 93 and the enlarged marginal portion 93c so as to permit the strip 93 to move with reference to the portion 93c for a purpose hereinafter explained. The casing 96 is preferably coextensive with the horizontal member 94 and is secured thereto in the desired manner, but the rubber strip 93 extends across the entire width of the window opening with its ends abutting the side jambs 14 of the window. The horizontal member 94 is secured in position along the lower edge of the air conditioning unit by means of one or more slots 98 formed in a vertical flange 99 thereof and adapted detachably to engage prongs 100 projecting from an angle member 101 carried by the lower end of the unit (see Fig. 4).

Each of the side members 95 is hinged to the horizontal member 94, as at 102, and includes an outer wall 104, an end wall 105 and an inner flange 106. The outer walls 104 of the side members constitute filler pieces for closing the spaces left between the sides of the unit and the side jambs of the window. When in position, the vertical marginal portions of the filler pieces 104 enter the outer sash grooves 20 while the upper marginal portions of the filler pieces, which are flush with the upper edge of the upper sealing cross member 87, enter the groove formed in the underside of the upper window sill and abut the vertical wall of the strip 92. The inner flanges 106 are provided with gaskets 107 which are similar to the gasket 91 and which abut the vertical sides of the unit as shown in Fig. 5. In order to seal the junction of the ends of the upper cross member 87 with the adjacent portions of the side members 95, the upper cross member is provided with end walls 108 and inner flanges 109 which abut the end walls 105 and flanges 106 of the side members 95, as shown at the top of Fig. 7.

As shown in Fig. 4, the junction of the end of the unit with the adjacent portion of the horizontal member 94 is sealed by means of a gasket 110 compressed between the vertical wall of an angle member 101 and an outer plate 111. The lower edge of the gasket 110 is preferably split so as to increase its sealing action and is pressed against the upper surface of the horizontal member 94, as shown in Fig. 4.

The weatherproofing means still further includes means for sealing the junction between the filler pieces 104 and the side jambs of the window. In the form illustrated, I use corner pieces 114, each of which, as best shown in Fig. 6, is formed of a rubber pad 115 clamped between two metal plates 116 by one or more bolts 118, the plates being dished as at 120.

Each pad 115 is provided with a marginal outer

portion 122 adapted to abut the adjacent portion of the adjacent side jamb 14 of the window, and an inner portion 124 adapted to abut the adjacent filler piece 104. The inner portion 124 is preferably wedge-shaped and is connected to the body of the pad by a relatively narrow hinge portion 126. The purpose of this structure and the manner of its operation will be hereinafter explained.

Each of the corner pieces is detachably secured in position by means of a clamp which has a U-shaped portion 128 adapted to engage the marginal portion of an adjacent filler piece, and a spring arm 130 which engages and clamps the wedge-shaped portion 124 of the pad against the adjacent portion of the filler piece.

In order to effect a tight seal between the outer portion 122 of the pad and the adjacent side jamb of the window, one or more pivoted spring latches 132 may be employed. The latches 132 are preferably carried by the bolts 118 and are rotatable to the position shown in Fig. 6, in which the free end of the latch bears against the filler piece and thus exerts a force which presses the portion 122 against the adjacent side jamb of the window.

To remove the corner pieces, it is merely necessary to disengage the latches 132 from the filler pieces and to disengage the wedge-shaped portion 124 from the respective clamps 128.

The corner pieces described are of such a length that, when in position, their upper ends abut the underside of the top window sill and their lower ends rest on the upper side of the lower sealing strip 93.

Assembly of weatherproofing means

When it is desired to mount the air conditioning unit in position, the filler pieces 104 are cut down so that when the side members 95 are moved to their vertical position, the filler pieces will completely close the space between the side walls of the unit and the sash grooves. The rubber strip 93 is then cut to size, so that its ends abut the side jambs of the window and the enlarged portion thereof is then inserted into the casing 96. The U-shaped clamps 128 are then applied to the marginal portions of the filler pieces 104, the wedge-shaped portion 124 of the marginal portions of the pads 115 being clamped by the spring arms 130. The weatherproofing structure is now tailored to fit the window and, after the unit has been mounted in position as above set forth, the upper cross member 87 is secured in position and the lower cross member 94 with the side members 95 normal thereto is then secured in position by engagement of the slots 98 with the prongs 100. When this is done, the flanges 106 of the side members abut the flanges 109 of the upper cross member, as shown in Fig. 7. The corner pieces 114 are then pushed against the respective side jambs and the latches 132 are turned so as to abut against the filler pieces 104, as shown in Fig. 6.

With the unit and the weatherproofing structure thus completely assembled, the outer window sash is raised until the upper edge portion forms a seal with the strip 93 and its flanges 93a and the inner window sash is lowered to close the remaining portion of the window opening.

When it is desired to raise the outer window sash for the purpose of window washing, or in order to close the upper portion of the window opening, it is merely necessary to rotate the latches 132 until they are disengaged from the

filler pieces 104, in which position they are disposed in the dished portions 120 of the clamping plates 116. The corner pieces may now be rotated about their hinge portions 126 until they abut or lie flat against the adjacent corner pieces, in which position they will be disposed inwardly of the outer sash groove. Likewise, the strip 93 being hinged to the enlarged portion 93c by the reduced portion 93b can now move downwardly so as to assume a position normal to the horizontal plane of the cross member 94. In this position, the strip 93 is also disposed inwardly of the outer sash groove. By this means, the outer window sash can be raised all the way up to the upper window sill without the necessity of removing any part of the weatherproofing structure and without in any way disturbing the mounting means of the unit itself.

When it is desired to remove the weatherproofing structure altogether, it is merely necessary to disengage the latches 132 and to disengage the slots 98 from the prongs 100, whereupon the lower cross member 94, the side members 95 and the corner pieces 114 can be removed as a unit. The upper cross member 87 can then be removed by merely disengaging the screws 89.

While I have shown my invention in but one form, it will be obvious to those skilled in the art that it is not so limited but is susceptible of various changes and modifications without departing from the spirit thereof.

What I claim is:

1. The combination with a room air conditioning unit, of means for mounting the same in a window, said means comprising vertical elongated members separate from the window, resting on the bottom of the window and extending upwardly to a point adjacent the top of the window, means for mounting said unit on said vertical members adjacent the upper ends thereof with the unit disposed primarily on the room side of the vertical members, said means including parts which transmit forces directed inwardly of the room from the unit to the vertical members at points adjacent the upper ends of the latter and parts which transmit forces directed outwardly of the room from the unit to the vertical members at points spaced downwardly from the first-mentioned points but spaced above the lower ends of the vertical members, whereby the turning moment imposed on said unit by the force of gravity is transmitted to the vertical members, and means providing engagement between the lower ends of said members and the bottom of the window and between the upper ends of said members and the top of the window for resisting the turning moment imposed on the vertical members by the unit, whereby the horizontal forces imposed on the window are substantially less than the horizontal forces imposed by the unit itself.

2. In combination, a room air conditioning unit adapted to be mounted in a window opening defined by a top sill, a lower sill and side jambs, vertically elongated members resting on said bottom sill and extending towards said upper sill, means securing said unit to the upper ends of said members for supporting the weight of the unit, and means engaging said upper sill and the adjacent portion of said unit for resisting the turning moment of said unit in the direction of the room, said unit being formed in the shape of an L with the horizontal limb of the L disposed in the uppermost portion of the window opening and with the vertical limb of the L extending upwardly

towards the ceiling of the room and adjacent to the wall of the room above the window opening, whereby the center of gravity of the unit is brought closer to the vertical plane of the elongated members and the turning moment of the unit is reduced.

3. In combination, a room air conditioning unit adapted to be mounted in a window opening defined by a top sill, a lower sill and side jambs, vertically elongated members resting on said bottom sill and extending towards said upper sill, means securing said unit to the upper ends of said members for supporting the weight of the unit, and means engaging said upper sill and the adjacent portion of said unit for resisting the turning moment of said unit in the direction of the room, said first-mentioned means including a cross member carried by the upper portions of the elongated members, and said second means including a bracket secured to the top sill of the window, to said cross member, and to said unit.

4. Means for mounting a room air conditioning unit in the upper portion of a window opening defined by a bottom sill, a top sill and side jambs, there being inner and outer grooves provided in said jambs and inner and outer sashes movable in said grooves, said means including upright members adapted to rest on and extending upwardly from the bottom sill and disposed along said side jambs, an upper cross member carried by the upper portions of said upright members, means secured to said unit and engaging the top sill of the window, and means for securing the last-mentioned means to said cross member, said vertical and cross members being disposed entirely outside of the planes defined by said grooves.

5. The structure recited in claim 4 together with a lower cross bar also carried by said upright members forming an abutment for the lower portion of the unit.

6. The structure recited in claim 4 together with means for effecting a seal between the unit and the surrounding portions of the window frame, and between the unit and the upper edge of said outer window sash, said means including a lower horizontal member adapted to be detachably secured to the adjacent portion of the unit, a gasket member carried by said horizontal member and adapted to engage the upper edge of said outer sash, vertical members hinged to said horizontal member and adapted to close the spaces left between the vertical sides of the unit and the side jambs of the window frame, and an upper horizontal member detachably secured to said upper cross member for sealing the junction of said top sill with the adjacent portion of the unit.

7. In combination, a room air conditioning unit adapted to be mounted in a window opening defined by a top sill, a lower sill and side jambs formed with inner and outer sash grooves, vertically elongated members separate from the window, resting on said bottom sill and extending towards said upper sill, means securing said unit to the upper ends of said members for supporting the weight of the unit, means engaging said upper sill and the adjacent portion of said unit for resisting the turning moment of said unit in the direction of the room, means for sealing the spaces between the sides of the unit and the side jambs of the window, and means for sealing the junction of the top of the outer window sash with the adjacent portion of the unit, said last-mentioned means comprising a sealing member hav-

11

ing a hingedly connected movable portion which engages the top of said outer window sash in sealing position and which is movable toward the room side of the plane of the outer sash grooves to permit the outer window sash to be raised to its uppermost position.
